UNITED STATES PATENT OFFICE

2,435,712

ICE PREVENTING MEANS FOR PROPELLERS

John De Stefano, Jackson Heights, N.Y.

Application May 2, 1945, Serial No. 591,433

4 Claims. (Cl. 244—134)

1

My invention relates to propellers for airplanes, seaplanes, helicopters and dirigibles, and more specifically to propeller de-icing apparatus of the type forming the subject matter of my U. S. Letters Patent No. 2,339,772, dated January 25, 1944, and over which the instant invention is designed as an improvement.

The primary object of the instant invention is to provide de-icing apparatus for such propeller blades especially adapted for discharging de-icing fluid forwardly of the blade along the leading edge thereof to effectively de-ice the leading edge and be thrown rearwardly and outwardly toward the tip of the blade so as to form a film over the entire blade.

Another object is to provide de-icing apparatus equipped with means for distributing de-icing fluid over the root end of the blade in case the apparatus fails to function as above set forth, or while the apparatus is so functioning, and so that the de-icing fluid will be thrown under the action of centrifugal force outwardly along the entire blade and directed toward the leading edge of said blade.

Still another object is to provide in such de-icing apparatus for directing the de-icing fluid discharged forwardly of the blade outwardly along the leading edge to the tip of the blade so as to effectively de-ice said edge.

Another object is to provide apparatus adapted to function efficiently in the manner set forth and which is of simple construction rendering the same inexpensive to manufacture and replace.

Other and subordinate objects, also comprehended by my invention, together with the precise nature of my improvements, and the manifold advantages thereof, will be readily understood when the succeeding description and claims are read with reference to the drawings accompanying and forming part of this specification.

In said drawings:

Figure 1 is a view in front elevation of a propeller embodying my improvements.

Figure 2 is a similar view of one of the propeller blades embodying the invention and drawn to an enlarged scale.

Figure 3 is a similar fragmentary view with parts shown in section and drawn to a further enlarged scale.

Figure 4 is a detail view in transverse section taken on the line 4—4 of Figure 3.

Figure 5 is a view in plan of the de-icing boot detached and shown in a spread-out condition.

Figure 6 is a view similar to Figure 2 illustrating a modification of the invention.

2

Figure 7 is a view in transverse section taken on the line 7—7 of Figure 6 and drawn to an enlarged scale.

Reference being had to the drawings by numbers, and first to Figures 1 to 5 thereof, the type of propeller shown as embodying my improvements comprises a hub 1 equipped with a concentric so-called slinger ring 2 rotating with the hub and having formed in the outer face thereof an annular groove 3 capped by an annular stationary shield 4, secured to the motor, not shown, by bolts 5, the groove 3 and the shield 4 forming a chamber for de-icing fluid to be thrown, under the action of centrifugal force, out of said ring 2 through nipples, as at 6, on the slinger ring 2. The nipples 6, for instance as best shown in Figure 3, are aligned, substantially, with the leading edges of the propeller blades 7. The blades 7 are mounted in blade sockets 8 on the hub 1. De-icing fluid, not shown, is supplied to the groove 3, or chamber, by a forced feed supply plant 9, usually located in the cockpit of an airplane, not shown, and including a fluid supply line 10 suitably connected to the shield 4.

According to the instant invention, the blades 7 are each provided with an elongated, clip-like boot 11 fitting over the leading edge 12 of the blade 7 in straddling relation thereto and extending from the root, or base, end 13 of the blade to substantially the tip end 14 of said blade. Each boot 11 comprises a pair of side flaps 15 diverging from what constitutes the leading edge 16 of the boot and tapering from substantially said edge 16, as best shown in Figure 4. At the inner end of the boot 11, the flaps 15 are widened to provide a split cuff portion 17 adapted to completely surround the root, or base, end portion 13 of the blade 7. The leading edge 16 of each boot 11 is thickened and terminates adjacent to the inner end of said boot in a manifold nipple 18 opening into the inner ends of a series of closely spaced small ducts 19 extending through said leading edge 16, longitudinally. Preferably, and as shown in Figure 4, three such ducts 19 are provided, with one duct extending along the longitudinal center of the leading edge 16 to within a short distance of the tip end of the boot 11 and the other ducts 19 extending alongside the first-mentioned duct and, as best shown in Figure 5, branching into the first duct at different distances from the manifold nipple 18 opposite small outlet ports 20 from the first-mentioned duct opening onto the leading edge 16 in the exact longitudinal center thereof. In this connection, other outlet ports 21 from the first-mentioned duct 19 are similarly provided in

the leading edge 16 and said ports 20, 21 are equidistantly spaced apart along said edge. A pair of small ribs 22 extend along the leading edge 16 upon opposite sides of the longitudinal center thereof and from the manifold nipple 18 to the tip end of the boot 11, said ribs 22 being spaced close together to provide a narrow shallow channel 23 along the leading edge 16 into which the outlet ports 20, 21 open for a purpose presently seen. A series of small external ribs 24, which may vary in number as desired, extend diagonally across the cuff portion 17 from the trailing edge of said portion and the inner end of the boot 11 to the leading edge 16 of said boot 11 adjacent the manifold nipple 18, said ribs preferably converging relatively toward said edge. The function of the ribs 24 will presently be described.

A fluid feeder line 25 connects the manifold nipple of each boot 11 with the adjacent nipple 6 with a coupling interposed therein forming a back-pressured discharge valve. The coupling 26 comprises a tubular body 27 having an axial bore 28 therein for feeding fluid therethrough to the manifold nipple 18, and an enlarged central portion 29 provided with longitudinal fluid return ducts 30 therein grouped around the bore 28, said ducts opening into a tubular sleeve 31 connecting the portion 29 to the manifold nipple 18, said ducts 30 having lateral, rear end outlets 32 opening into an annular forwardly flaring spreader 33 surrounding the portion 29. A tubular sleeve 34, similar to the sleeve 31 connects the coupling 26 to the nipple 6, the sleeves 31 and 34 being arranged at opposite sides of the spreader 33 so as to leave the spreader 33 exposed. The arrangement of the coupling 26 is such that the same is close to the cuff portion 17 and the spreader 33 opens toward said portion.

The entire boot described is preferably formed of rubber, or like material, and secured to the blade 7, preferably by cement, not shown. The sleeves 31, 34 are also formed of rubber, or rubber composition, preferably.

Referring now to the operation of the invention as described in the foregoing. With the propeller revolving, the de-icing fluid is forced under pressure out of the groove 3, and the nipples 6 through the feeder lines 25 to the manifold nipples 18 which feed the fluid into the ducts 19 from which the fluid is discharged through the outlet ports 20, 21 into the channels 23. The de-icing fluid being supplied under sufficient pressure, overflows out of the channels 23 to be distributed, by revolution of the blades 7 and under the action of centrifugal force, over the flaps 15 and the exposed portions of the blades 7. Also, the de-icing fluid is caused, under the action of centrifugal force, to flow along the channels 23 toward the tip ends of the blades 7, thereby facilitating distribution of the de-icing fluid over the flaps 15 and blades 7 to the tip ends of said blades. Should the discharge ports 20, 21 become clogged, for any reason, the de-icing fluid will back up in the manifold nipples 18 and the sleeves 31 and discharged through the ducts 30 and ports 32 into the spreaders 33 and be directed by said spreaders onto the cuff portions 17. In this event, the de-icing fluid will be thrown under the action of centrifugal force along the flaps 15 and blades 7 toward the tips 14 of said blades and also be directed by the ribs 24 to the leading edges 16 of the boots 11 to flow along said leading edges toward the outer ends of the boots 11. Thus, the de-icing operation will be effected independently of the ducts 19 and outlet ports 20,

10 21 in the event that such ducts and outlet ports fail. However, by supplying the de-icing fluid to the groove 3 under pressure such that the discharge is choked at the outlet ports 20, 21, the described de-icing operation effected under back pressure may also be accomplished in conjunction with de-icing through the ducts 19 and outlet ports 20, 21, the advantage of which will be obvious, particularly where heavy sleet storms and the like are encountered in navigating aircraft.

In the modification of the invention shown in Figures 6 and 7, the construction and arrangement is substantially the same as that previously described, with the exception that the boot 35 has the form of a cuff completely surrounding the propeller blade 36 for the greater portion of its length, as shown.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. In a propeller for airplanes and the like, a hub including a storage chamber for de-icing liquid, a propeller blade on said hub, a de-icing boot fitting over said blade and having a leading edge extending along the leading edge of the blade, longitudinal ducts in the leading edge of said boot terminating in outlet ports spaced apart along the leading edge of the boot, means common to all of said ducts for establishing communication between said chamber and the ducts comprising a manifold on the leading edge of the boot and from which said ducts extend, an exposed liquid feeder line from said chamber to said manifold, and a device in said line for discharging de-icing liquid onto said boot adjacent the root end of the blade under back pressure in said ducts.

2. In a propeller for airplanes and the like, a hub including a storage chamber for de-icing liquid, a propeller blade on said hub, a de-icing boot fitting over said blade and having a leading edge extending along the leading edge of the blade, longitudinal ducts in the leading edge of said boot terminating in outlet ports spaced apart along the leading edge of the boot, means common to all of said ducts for establishing communication between said chamber and the ducts comprising a manifold on the leading edge of the boot and from which said ducts extend, a liquid feeder line from said chamber to said manifold, a device in said line for discharging de-icing liquid onto said boot adjacent the root end of the blade under back pressure in said ducts, and means on said boot for directing the de-icing liquid discharged onto said boot diagonally thereof toward the leading edge of the same under the action of centrifugal force.

3. A de-icing boot for use on a propeller blade comprising a clip-like elongated member adapted to straddle said blade and having a leading edge portion adapted to extend along said edge of the blade, longitudinal ducts in the leading edge of the boot terminating at one end in outlet ports spaced apart along the leading edge of the boot, a manifold nipple on said leading edge of the boot adjacent one end of the boot and opening into the other ends of said ducts, said nipple being adapted for introducing de-icing liquid into said ducts, and a pair of ribs extending along

said leading edge of the boot and forming a channel into which said ports open.

4. A de-icing boot for use on a propeller blade comprising a clip-like elongated member adapted to straddle said blade and having a leading edge portion adapted to extend along said edge of the blade, longitudinal ducts in the leading edge of the boot terminating at one end in outlet ports spaced apart along the leading edge of the boot, a manifold nipple on said leading edge of the boot adjacent one end of the boot and opening into the other ends of said ducts, said nipple being adapted for introducing de-icing liquid into said ducts, and a pair of ribs extending along said leading edge of the boot and forming a channel

into which said ports open, said boot having a cuff portion at one end thereof adapted to surround the root end of a propeller blade.
